CUFF LINK CONSTRUCTION

Le Roy Joseph Salisbury, Olneyville, R. I., assignor to Freeman Daughaday Company, a corporation of Massachusetts

Application October 6, 1937, Serial No. 167,578

6 Claims. (Cl. 24—102)

My present invention relates to the jewelry art, and has particular reference to a novel construction of cuff link of the type having a movable head and a fixed head.

5 It is the principal object of my invention to provide a construction for a cuff link that facilitates manufacture and assembly of the parts and reduces the cost of manufacture.

10 It is a further object of my invention to provide a construction which permits the use of cuff link heads of various sizes and shapes.

15 It is an additional object of my invention to improve the construction of cuff link heads so as to facilitate mounting of ornaments at the end thereof.

Another object of my invention is to provide a construction for obtaining a universal movement of one cuff link head.

With the above and other objects and advantageous features in view, my invention consists of a novel arrangement of parts more fully disclosed in the detailed description following, in conjunction with the accompanying drawing, and more specifically defined in the claims appended thereto.

25 In the drawing,

Fig. 1 is a plan view of a novel cuff link constructed in accordance with my invention;

Fig. 2 is a side view thereof;

30 Fig. 3 is an enlarged detail longitudinal section of Fig. 1;

Fig. 4 is a section on the line 4—4 of Fig. 3;

Fig. 5 is a perspective view showing the construction of the movable head parts;

35 Fig. 6 is an enlarged section detail showing one form of mounting an ornament in the head end;

Fig. 7 is a detail, partly broken away and in section, of a swivel connection for the relatively fixed cuff link head; and

40 Fig. 8 is a perspective view of a modified structure.

It has been found desirable to construct a cuff link having a movable head, by utilizing separate sections for the movable head which are firmly locked together so as to simulate the appearance of an integral one piece head. I have devised an open top container portion and an outer cover portion which completely encircles the container 45 portion, whereby the assembly of the parts of the cuff link is greatly facilitated. I have also improved the construction of the upper fixed head, by providing a swivel connection therefor.

55 Referring to the drawing, the movable cuff

link 10 comprises an intermediate section 11, a movable head 12 which is rotatably journaled at one end of the intermediate portion 11 and is selectively movable to a position parallel to the intermediate section and at right angles thereto, and a relatively fixed head 13, which may be of any material and of any size. The intermediate section 11 is preferably made of wire, but may be made of stamped metal, and is formed with two parallel sides 14 joined by an integral end 15, the sides 14 being brought together at their lower ends as indicated at 16, Fig. 2, and soldered, riveted, or otherwise secured to an ornament retainer plate 17, in which an ornament 18 is seated to form the fixed head 13. The end 15 is preferably rectangular in section for a purpose hereinafter described.

The movable head 12 comprises a container 19, see Fig. 5, of general box shape and having an open top, the sides 20 of the container having aligned slots 21; the container material may be relatively inexpensive and preferably brass, and has end faces 22 secured thereto of more expensive material, if desired. A cover 23, made out of stamped metal and shaped as indicated in Fig. 5, is provided, having a top 24, sides 25 and bottom portions 26, the sides 25 and the bottom portions 26 being formed with aligned slots 27 which are adapted to align with and to cooperate with the slots 21 of the container 19. In assembling the movable head to the intermediate section 11, an arcuate spring 28 of generally rectangular form is positioned at the bottom of the container 19, and the container is then placed so as to bring the end 15 in the slots 21; a second spring 29 is then positioned in the upper end of the container, and the cover 23 is then mounted over the container 20, with its slots 27 aligned with the slots 21 and passing over the end 15; the bottom portions 26 are then brought together in adjacency, and are ornamented or otherwise treated as by plating or the like so as to conceal the seam formed by the join, whereby the completed movable head simulates an integral one piece head.

The construction above described provides a sturdy, strong arrangement of parts for selectively retaining the movable head in desired position relative to the intermediate section 11, as the two springs 28 and 29 press on opposite sides of the end 15 for releasably holding the movable head in position parallel to and perpendicular to the intermediate section. The construction permits the formation of the movable head in any shape desired, as the cover 55

locks together over and completely conceals the container. Moreover, the construction facilitates the use of ornamental ends for the movable head, as the container 28a may have its ends open, as indicated in Fig. 6, whereby a stone or other ornament 30 may be seated against each open end of the container and the ends of the cover 28a may then be wedged over as indicated at 31 to securely lock the ornaments in place.

If desired, the fixed head may have a universal mounting, as illustrated for example in Fig. 7, the base 17a being formed as a spherical open ended socket for receiving a ball 32 having the head 33 secured thereto as by a narrow neck portion 34.

While I have described a specific construction embodiment of my invention, it is obvious that changes in the arrangement of the parts may be made, as for example illustrated in Fig. 8. The container 32 in this modification, is open at the sides, and has a base 33 and two closed end cups 34, 35; with this construction, one spring may be inserted into the container, the 25 container and the intermediate section assembled, and the other spring then inserted, whereby the assembly of the parts is greatly facilitated.

Changes in the size and shape of the parts, 30 in the materials used, and in the ornamentation of the parts, may be made to suit the requirements for different cuff link designs, without departing from the spirit and the scope of my invention as defined in the appended claims.

35. I claim:

1. In a cuff link construction having a shank with spaced arms joined at one end by an integral rectangular bar, a movable head pivotally mounted on said bar, said movable head comprising a container having sides, bottom, and an open top, and a cover enveloping said container and having edges abutting to form a longitudinal seam, said container and said cover having side slots to permit assembly around said bar.

45. 2. In a cuff link construction having a shank with spaced arms joined at one end by an integral rectangular bar, a movable head pivotally mounted on said bar, said movable head comprising a container having sides, bottom, and an open top, and a cover enveloping said container and having edges abutting to form a longitudinal seam, said container and said cover having side slots to permit assembly around said bar, said movable head and said bar having cooperating parts engageable to selectively retain said movable head either in the plane of or at right angles to the shank.

3. In a cuff link construction having a shank with spaced arms joined at one end by an integral rectangular bar, a movable head pivotally mounted on said bar, said movable head comprising a container having sides, bottom, and an open top, and a cover enveloping said container and having edges abutting to form a longitudinal seam, said container and said cover having side slots to permit assembly around said bar, said movable head having parts engageable with the sides of said bar to selectively retain said movable head either in the plane of or at right angles to the shank.

4. In a cuff link construction having a shank with spaced arms joined at one end by an integral rectangular bar, a movable head pivotally mounted on said bar, said movable head comprising a container having sides, bottom, and an open top, and a cover enveloping said container and having edges abutting to form a longitudinal seam, said container and said cover having side slots to permit assembly around said bar, said movable head having spring means engageable with the sides of said bar to selectively retain said movable head either in the plane of or at right angles to the bar.

5. In a cuff link construction having a shank with spaced arms joined at one end by an integral rectangular bar, a movable head pivotally mounted on said bar, said movable head comprising a container having sides, bottom, and an open top, and a cover enveloping said container and having edges abutting to form a longitudinal seam, said container and said cover having side slots to permit assembly around said bar, said movable head having longitudinal springs seated therein and engageable with the sides of said bar to selectively retain said movable head either in the plane of or at right angles to the bar.

6. In a cuff link construction having a shank with spaced arms joined at one end by an integral rectangular bar, a movable head pivotally mounted on said bar, said movable head comprising a container having sides, bottom, and an open top, and a cover enveloping said container and having edges abutting to form a longitudinal seam, said container and said cover having side slots to permit assembly around said bar and ornaments having thin bases seated on the ends of said container, the cover of said container engaging the ornament bases to lock said ornaments in said head.

LE ROY JOSEPH SALISBURY. 55
